UNITED STATES PATENT OFFICE

150,561

DESIGN FOR A GAS STOVE

Richard I. Felver, Pittsburgh, Pa., assignor to
Standard Gas Equipment Corporation, Balti-
more, Md., a corporation of Maryland

Application September 26, 1946, Serial No. 133,593

Term of patent 14 years

(Cl. D81—4)

To all whom it may concern:

Be it known that I, Richard I. Felver, a citizen of the United States, residing at Pittsburgh, county of Alleghany, State of Pennsylvania, have invented a new, original, and ornamental Design for a Gas Stove, of which the following is a specification, reference being had to the accompanying drawing, forming part thereof.

Both sides of the stove are of substantially identical appearance.

Figure 1 is a view in perspective of a gas stove showing my new design.

Figure 2 is a slightly enlarged fragmentary view of the front side edge of the stove shown in Figure 1.

Figure 3 is a cross sectional view taken on the line 3—3 of Figure 1.

I claim:

The ornamental design for a gas stove, as shown and described.

RICHARD I. FELVER.
